UNITED STATES PATENT OFFICE.

JOSEPH VON ALT, OF CLEVELAND, OHIO, ASSIGNOR TO THE F. W. WAKEFIELD BRASS COMPANY, OF VERMILION, OHIO, A CORPORATION OF OHIO.

DESIGN FOR A LIGHTING FIXTURE.

Application filed February 10, 1928. Serial No. 25,339. Term of patent 7 years.

To all whom it may concern:

Be it known that I, JOSEPH VON ALT, a citizen of the United States, and a resident of Cleveland, county of Cuyahoga, and State of Ohio, have invented a new, original, and ornamental Design for Lighting Fixtures, of which the following is a specification, reference being had to the accompanying drawing, forming part thereof.

In said annexed drawing:—

The single figure there appearing is a side elevation of a lighting fixture showing my new design.

I claim:—

The ornamental design for a lighting fixture as shown.

Signed by me, this 9th day of February 1928.

JOSEPH VON ALT
